UNITED STATES PATENT OFFICE.

STEPHAN BROICHGANS, OF MILWAUKEE, WISCONSIN.

BURGLAR-ALARM.

SPECIFICATION forming part of Letters Patent No. 430,373, dated June 17, 1890.

Application filed March 21, 1890. Serial No. 344,706. (No model.)

To all whom it may concern:

Be it known that I, STEPHAN BROICHGANS, of Milwaukee, in the county of Milwaukee, and in the State of Wisconsin, have invented 5 certain new and useful Improvements in Burglar-Alarms; and I do hereby declare that the following is a full, clear, and exact description thereof.

My invention relates to burglar-alarms; and 10 it consists in certain peculiarities of construction, as will be fully set forth hereinafter, and subsequently claimed.

In the drawings, Figure 1 is a rear elevation of my device with parts broken away or in 15 section. Fig. 2 is a vertical transverse section on the line 2 2 of Fig. 1. Fig. 3 is a vertical section on the line 1 1 of Fig. 2, showing also electrical connections with a window; and Fig. 4 is a detail view showing the manner of 20 attachment of one of the revolvers. Fig. 5 is a detail view of the cam-edge flanged plate and its shaft.

My present invention is an improvement on 25 that class of devices shown in my prior Patent No. 321,679, dated July 7, 1885, wherein a fire-arm is discharged when a door or window connected with the alarm is opened; but in my present device the connection between said door and window and said alarm is an elec- 30 trical one, the opening of the door or window serving to make contact and close an electric circuit, and thereby automatically release a detent and permit my device to operate.

A is the front plate of my device, which plate 35 is provided with a series of perforations *a*, preferably four in number, located at the corners of a supposed square. B is the back plate, provided with a like number of perforations similarly arranged, and having, preferably, 40 surrounding sockets *b* on the inner side, said sockets *b* and perforations *a* being designed to receive the barrels C of self-cocking revolvers D, two of which are inserted, lying sideways, with their handles pointing in opposite directions, one in ordinary position, and the fourth one inverted, as clearly indicated by the relative positions of the feathers *c*, normally on the tops of the revolver-barrels, so that each revolver-trigger (which is extended 45 into a lever-arm *d*) shall point in a different

direction, but continuously around the square outlined by the perforations *a* back of the back plate B, on the rear face of which are projecting lugs, to which are pivoted arms forming double toggle-levers for operating 55 the trigger lever-arms *d*, as hereinafter described, the said back plate being further provided with L-shaped slots *L*, continuously grouped around its central part to receive the cam-pins *E* and their arms *e*, connected to said 60 double toggle-levers.

The two plates A and B are connected by a series of posts F F F and screws or screw-bolts *f*, like a clock-frame, and at their upper parts by the spring-shaft G, which receives the hub 65 of the gear-wheel H, to which the casing I of the spring *i* is secured, (said wheel H forming one wall of said casing,) the adjacent end of said shaft G projecting through the plate A and being squared, as shown at *g*, to receive 70 a winding-key, and on the other side of this casing I this shaft G carries a ratchet-wheel *h* for engagement with a pawl *J*, pivoted to a pin on the inner face of the back plate B, as shown in dotted lines in Fig. 1, and held 75 against said ratchet-wheel by a spring *j*.

The plates A B are provided with central sockets *k* *k* for a shaft K, which has secured to it the hub *m* of a plate having a peripheral flange *M*, with a cam-edge for engagement 80 with the cam-pins *E*, already named. On the other side of said plate is a gear-wheel N, whose teeth mesh with those of the gear-wheel H on the shaft G above, and next this wheel N, on the same shaft K, is an escapement- 85 wheel O, the cam-plate M, wheel N, and wheel O being all connected rigidly together by pins *n* *n*, and the motion of the wheel O being governed by the pallets of an ordinary escapement *o*, pivoted at *p* to the plate A and having a weighted pendulum P depending therefrom.

Q Q represent electro-magnets suitably supported between the plates A B on a frame *q*, and R is a lever pivoted at *r*, the upper end 95 of which ends in a detent *s*, which may be held normally (as by spring *s'*, pivoted at *s'* to the plate A or by gravity) in engagement with the teeth of the gear-wheel N, and the lower end of which terminates in an arma- 100

ture S, projecting adjacent to the ends of the magnets Q Q and within their field of magnetic attraction when they are energized.

The double toggle-levers hereinbefore referred to are all exactly alike, save in location, that being arranged to conform to the location of the trigger lever-arm d, with which each engages, said device comprising a straight link t, arm T, having a curved end 10 pivoted to said link t, and a Y-shaped part comprising a straight stem u, an oblique arm U, pivoted to the straight end of the arm T, and an oblique cam-pin arm e, terminating in a cam-pin E, projecting at right angles therefrom, (the parts e E having already been referred to,) and the links t and stems u of the said double toggle-levers being pivoted to lugs V v, respectively, on the rear of the back plate B.

20 The operation of my device will be readily understood from the foregoing description of its construction, taken in connection with the accompanying drawings. The revolvers are all loaded, preferably with blank cartridges, 25 (the object being chiefly to create an alarm and make a noise,) and placed in proper position, the spring i wound up, and the detents s caught in the toothed periphery of the wheel N. The device may be secured at any 30 convenient point, preferably adjacent to the door or window which it is sought to guard.

W w represent the upper and lower sash of a window, each having metallic contact-pieces secured thereto of any approved construction, (such as the fork X and tongue x,) so that when the window is closed these parts will not be in contact, but the slightest movement of either sash being sufficient to bring them into contact, said contact-pieces being 35 connected by wires Y y with the electro-magnets Q Q and with an electric battery Z, so that the moment contact between the pieces X x is made, as described, the magnets Q Q are energized and the armature S on the end 40 of lever R attracted thereto, thereby withdrawing the detent s on the other end of said lever R from engagement with the toothed rim of wheel N and permitting the spring i to set the train of gearing in motion, as a result 45 of which the cam-flanged plate M is revolved on its shaft K, (through the gears H N,) and this cam-flange, acting on the cam-pins E, operates the double toggle-levers e u U T t, and the arms T thereof in turn successively actuate the trigger lever-arm d of 50 the revolvers D, thereby successively firing said revolvers until all the cartridges are exploded. Of course, if desired in any instance, the device may be set in such position that, 55 being loaded with ball-cartridges, it will be a real battery instead of a mere alarm, this being merely a matter of location and judgment, and the device can be stopped at any time by breaking the circuit and permitting the detent s to again engage with the wheel N.

60 Though shown with a window, it will be understood that my device may be as easily

electrically connected to a door. If desired, a bell-ringing device may be also attached, practically as in my said prior patent, herein- 70 before referred to.

Having thus described my invention, what I claim as new, and desire to secure by Letters Patent, is—

1. In a burglar - alarm, the combination, 75 with a suitable supporting-frame, a spring and its casing supported on a shaft in said frame, and a gear-wheel on said shaft, of a lower shaft carrying a plate having a cam-edged flange, a gear-wheel in mesh with the one above, and an escapement-wheel, an escapement connected to a weighted pendulum, an electro-magnet electrically connected to the door or window to be protected, a pivoted lever having a detent for one of the 80 gear-wheels at one end and an armature at the other end, and a double toggle-lever for operating the alarm pivoted to said frame and having an arm or pin for engagement with said cam-edged flange, substantially as 85 set forth.

2. In a burglar - alarm, the combination, 90 with a suitable supporting-frame and a series of fire-arms supported therein, of a shaft carrying a spring-casing, a gear-wheel, and a 95 ratchet-wheel, a spring in said casing, a pawl on said frame in engagement with said ratchet-wheel, another shaft carrying a plate having a cam-edged flange, a gear-wheel, and an escapement-wheel, all rigidly secured together, said gear-wheel being in mesh with the one on the other shaft, an escapement connected to a weighted pendulum, magnets electrically connected to the door or window to be protected, a pivoted lever having a detent for one of said gear-wheels at one end 100 and an armature at its other end, and a series of double toggle-levers pivoted to said frame and having projecting arms with pins lying in the path of the said cam-edged flange, 105 said levers being in contact with the triggers of said fire-arms, substantially as set forth.

3. In a burglar - alarm, the combination, 110 with a suitable supporting-frame and a fire-arm supported therein, of a double toggle-lever in contact with the trigger of said fire-arm, a train of gearing, and a cam-plate connected thereto for operating said lever, a lever having a detent at one end in engagement with said gearing and an armature at 115 its other end, an electro-magnet adjacent to said armature, and a battery electrically connected to said magnet for energizing the latter and thereby freeing the detent at the 120 proper time, substantially as set forth.

In testimony that I claim the foregoing I have hereunto set my hand, at Milwaukee, in the county of Milwaukee and State of Wisconsin, in the presence of two witnesses.

STEPHAN BROICHGANS.
